MECHANICALLY FED LEAD PENCIL

Filed July 12, 1926

UNITED STATES PATENT OFFICE

ROY C. STOWE, OF PROVIDENCE, RHODE ISLAND, ASSIGNOR TO A. T. CROSS PENCIL CO., OF PROVIDENCE, RHODE ISLAND, A CORPORATION OF RHODE ISLAND

MECHANICALLY-FED LEAD PENCIL

Application filed July 12, 1926. Serial No. 121,771.

This invention relates to an improvement in the construction of mechanically fed lead pencils; and has for its object to provide in such a pencil a point end member for securing 5 the lead-propelling movement in the barrel of the pencil.

A further object of the invention is the housing of the mechanical movement in a tubular member attached to the stub or eraser 10 end of the pencil which assembles the lead propelling movement as a unit and through which the lead is operated.

With these and other objects in view, the invention consists of certain novel features of 15 construction, as will be more fully described, and particularly pointed out in the appended claims.

In the accompanying drawings:

Figure 1 is a sectional elevation of the pencil with portions broken away to better illustrate its construction.

Figure 2 is a side elevation of the propelling movement which is secured in the barrel portion.

25 Figures 3, 4, 5, 6, 7, 8, and 9 are details of different working parts of the pencil.

Figure 10 is a sectional side elevation illustrating the details heretofore mentioned assembled with the exception of the point end 30 member Figure 7.

It is found in the manufacture of mechanically actuated pencils desirable to eliminate as many soldering operations in the assembly of the pencil as possible and also desirable to have the entire propelling movement in unit form such that it may be readily assembled or placed in the barrel of the pencil to be locked or held therein, and by providing a threaded portion at the end of the bushing member of 35 the propelling movement and providing a threaded point end member to be screwed onto the threaded end, simple and effective means are provided for securing the propelling unit in its casing and so reducing the 40 cost of manufacture in assembling the pencil parts; and the following is a detailed description of the present embodiment of this invention and showing one construction of pencil 45 by which these advantageous results may be 50 accomplished:—

With reference to the drawings, 10 designates the barrel portion or body of a pencil with a tapered sleeve 12 attached to one end of the barrel through the plug 11. In a pencil having a metal barrel the sleeve and barrel 55 portion might be one piece if desired thus doing away with the necessity of the connecting plug 11 which I employ where a non-metallic barrel is used.

Figure 2 illustrates a complete propelling 60 movement unit which comprises a bushing 13 and a housing portion 14 rotatable relative to the bushing for propelling the lead of the pencil. The bushing member 13 which is shaped externally to fit the tapered sleeve 12 65 threaded throughout its length as at 15^a to be secured onto the threaded end 15 of the tube 19, the sleeve being further secured on the tube by solder, if desired. In order to draw this tapered bushing down into the 70 sleeve 12 sufficiently to bind and hold it against rotation therein, I have provided a point end member 16 which is preferably formed of a solid piece of metal with a threaded opening 17 to be screwed into the 75 threads 15 on the extending end of the guide tube and also with a shoulder 18 to engage the end of the tapered sleeve. Also this point end member is provided with a reduced portion 80 32 arranged to extend up into the end of the sleeve to support and center the end member relative to the adjacent parts.

This guide tube 19 is mounted within the housing member 14 and in this tube there is 85 slidably mounted lead carrier 20 and ejector 21, each having a finger 22 and 23 respectively, to be guided in the slot 24 in the tube.

A worm or screw 25 is rotatably mounted about the tube 19 and held against displacement by means of a ring or washer 31. This 90 screw has a helical groove 26 which receives the fingers 22 and 23 of the lead carrier and ejector. The housing 14 envelops the screw 25 to frictionally engage the screw as at 27 so that a rotating movement of the housing 95 will transmit a corresponding movement to the screw to operate the lead carrier of the pencil.

At the opposite end of the housing 14 there is mounted a head member 28 which com-

prises a tubular eraser-receiving cup 29 and a cap 30 thereover and this head member is rotatable relative to the barrel 10 to impart a rotative movement for retracting or propelling and expelling the lead 32 in the lead carrier in the manner as will be apparent from the above description.

It will thus be seen that I have provided a mechanically operated pencil in which the propelling movement is a complete unit which may be placed within the barrel of the pencil and locked therein by a point end member without the use of solder. The point end member may be made solid and of steel if desired to provide a protection for the lead, while the sleeve and head end member or a non-metallic barrel, as illustrated, or the entire barrel and sleeve may be made of precious metal for ornamentation.

20 The foregoing description is directed solely towards the construction illustrated, but I desire it to be understood that I reserve the privilege of resorting to all the mechanical changes to which the device is susceptible, 25 the invention being defined and limited only by the terms of the appended claims.

I claim:

1. In a mechanically operated pencil, a barrel portion, a tapered sleeve secured to one 30 end thereof, a tapered bushing in said sleeve, a lead propelling movement in said barrel including a guide tube threaded through said bushing, a point end member having a shoulder engaging the end of said tapered sleeve 35 and screwed onto the threaded end of said tube to draw the same into the sleeve and secure it against rotation relative to said sleeve or barrel.

2. In a mechanically operated pencil, a 40 barrel portion, a tapered sleeve secured to one end thereof, a tapered bushing in said sleeve, a lead propelling movement in said barrel including a guide tube threaded on its end and threaded thru said bushing, a worm ro- 45 tatably mounted on and secured to said guide tube, a point end member having a shoulder engaging the end of said tapered sleeve and screwed onto the threaded end of said guide tube to draw the same into the sleeve and secure it against rotation relative to said sleeve or barrel.

3. In a mechanically operated pencil, a 50 barrel ending in a tapered sleeve portion, a lead propelling movement unit including a 55 tapered bushing in said sleeve portion and a threaded member secured to and projecting beyond said bushing, and a point end member engaging said threaded member for securing said movement in said barrel.

60 In testimony whereof I affix my signature.
ROY C. STOWE.
